UNITED STATES PATENT OFFICE.

HARRISON BUCKLIN, OF ROCHESTER, NEW YORK.

WAGON.

1,297,438.

Specification of Letters Patent. Patented Mar. 18, 1919.

Application filed June 27, 1916. Serial No. 166,142.

To all whom it may concern:

Be it known that I, HARRISON BUCKLIN, of Rochester, in the county of Monroe and State of New York, have invented certain new and useful Improvements in Wagons; and I do hereby declare the following to be a full, clear, and exact description of the same, reference being had to the accompanying drawings, forming a part of this specification, and to the reference characters marked thereon.

My invention relates to improvements in wagons and particularly toy wagons and has for its object to provide a wagon which may either be drawn by a tongue or foot propelled and steered by an occupant thereof. A further object of the invention is to provide a steering mechanism for a wagon having connected therewith a draft member movable to a position beneath the wagon independently of the movement of the steering mechanism. To these and other ends the invention consists in certain improvements and combinations of parts, all as will be hereinafter more fully described, the novel features being pointed out in the claims at the end of the specification.

In the drawings:

Figure 1 is a side elevational view of a wagon embodying the invention;

Fig. 2 is a plan view thereof;

Fig. 3 is a front elevational view of the same;

Fig. 4 is a sectional view taken on line *a—a* of Fig. 3;

Fig. 5 is an enlarged detail sectional view taken on line *b—b* of Fig. 3;

Fig. 6 is a view in elevation of an operating member for controlling the steering mechanism.

Similar reference characters throughout the several views indicate the same parts.

Referring to the drawings by numerals, 1 represents the body of the wagon which may be of any preferred design and which is mounted upon the front and rear supports or beams 2 and 3 respectively, carried by the bolsters 4 and 5 as shown. Suitable cross beams 6 and 7 are positioned beneath the body to which are secured the downwardly inclined braces 8 and 9 suitably connected at their bottom ends to the front and rear bolsters 4 and 5 respectively. The rear bolster 5 is carried by the axle 10 on which the wheels 11 are mounted. The front bolster 4 is provided, around its bottom and

side edges, with a reinforcing plate or strap 12, the upper ends of which are turned out at 13 and suitably connected with the under surface of the body support 2. The bolster 4 is mounted a little ahead of the center of the front wheels 14 as shown in Fig. 4, and is provided with outwardly and downwardly extending brackets 15 carrying spaced horizontally disposed lugs or extensions 16. The lugs preferably extend rearwardly of the bracket and are provided with registering openings through which a pivot pin 17 is positioned and upon which pin the vertically disposed axle heads or knuckles 18 are pivotally mounted. The axle heads are preferably T-shaped and carry the stub axles 19 which are mounted in suitable ball bearing casings 20 and 21 spaced apart and seated in the depressed pockets of the hub-plates 23 which are mounted upon opposite sides of the center of the wheels. The steering mechanism for the wagon comprises a steering post 32 journaled in a bearing member 33 which is preferably recessed to receive the supporting straps 34 and 35 which are suitably connected with the front face of the bolster 4 at its bottom edge, said straps forming a support for the bearing member as well as a bearing upon which said member is rotatably mounted. A steering arm 36 is rigidly mounted upon the steering post by means of the pins 37, the arm being adapted to project through an opening 38 in the bolster 4 as shown in Figs. 4 and 5. The rear end of the arm 36 is provided with a pivot bolt 39 upon which is pivotally mounted a steering rod 40, the opposite ends of which are pivotally connected at 41 with the rearwardly projecting arms 42 carried by the axle heads 18. The steering post extends upwardly in front of the body of the wagon to a point adjacent to the top thereof and is provided with lateral projections 43 as shown in Fig. 3. An operating member for the steering post comprises a tubular rod 44, the free end of which is adapted to be inserted upon the upper end of the steering post, the projections 43 being received in slots or recesses 45 formed in the tubular member to provide means for turning the steering post in opposite directions. The top of the tubular member 44 is connected with a head 46 from which projects the oppositely positioned and laterally extending handles 47 which are preferably removable. An additional han-

dle 48 is removably connected with the head 46 and projects rearwardly of the steering post. The handle 48 may be used when it is desired to steer the wagon by one hand 5 and the handles 47 are to be used when it is desired to steer by both hands. A guide 49 for the steering post is mounted upon the cross beam 2 and secured thereon by suitable bolts or screws. The bearing member 33 is adapted to extend below the bottom of the bolster 4 to terminate in a squared portion 50 and rigidly connected with the squared portion and adapted to project therefrom is a tongue support 51, 15 upon which is pivotally mounted at 52 a tongue 53 by which the wagon may be drawn. The tongue support 51 is preferably channel shaped, the flanges of the channel being adapted to engage the opposite 20 sides of the squared portion 50 and are secured thereon by suitable rivets or bolts 54. The web 55 of the channel is provided with an opening to allow the lower end of the steering post to extend therethrough. A 25 cotter pin 56 is positioned through the steering post beneath the tongue support to secure said post upon the bearing member. In order to prevent the turning of the bearing member 33 upon the steering post when 30 the wagon is being drawn by the tongue, I position through the enlarged portion 57 of the steering arm 36 a locking pin 58 which is adapted to extend into a recess formed in the top of the bearing member as shown in 35 Fig. 5. The pin is adapted to be held in locking engagement with the bearing member by a coil spring 59, the lower end of which is seated in a notch or recess 60 formed in the top of the pin, while the upper end of the spring is adapted to extend 40 through the steering post and is bent or turned up at 61 and shouldered at 62 to prevent displacement. The recess in the top of the bearing member 33 is positioned so 45 as to receive the lower end of the pin 58 only when the tongue of the wagon is extending forwardly and centrally of the body. By lifting the pin from the position shown in Fig. 5, the tongue and bearing 50 member 33 may be turned upon the steering post until said tongue assumes the position indicated by dotted lines in Fig. 5, or as shown beneath the body in Fig. 1. With the tongue in this position the wagon is intended to be pushed by the foot of the occupant thereof, and at the same time steered by either the laterally extending handles 47 or the rearwardly projecting handle 48. With the tongue positioned beneath the 55 body the outer end thereof is adapted to be supported by a suitable strap or hook 63 secured to the rear bolster 5. It will be understood that with the pin 58 in locking engagement with the bearing member 33 60 movement of the tongue 53 to the right or

left of the center of the wagon will cause the steering rod 40 to shift the wheels 14 upon the pivot pins 17. Likewise upon turning the steering post 32 by means of the handles the same result will be accomplished. 70

I claim as my invention:

1. A wagon provided with a steering mechanism and a draft member revolvably connected therewith to be movable thereon 75 to a position beneath the wagon.

2. A wagon provided with a steering mechanism and a draft member revolvably connected therewith to be movable thereon 80 independently of the movement of the steering mechanism.

3. In a wagon, the combination of a bolster, steering mechanism journaled thereon, a draft member revolvably connected with 85 said steering mechanism and movable independently thereof, and means for locking the steering mechanism to the draft member.

4. In a wagon, the combination of a bolster, a bearing member revolvably supported thereon, a steering post in said bearing member, wheels on which said bolster is supported, means operatively connecting said steering post with the wheels, and a draft 90 member mounted on said bearing member. 95

5. In a wagon, the combination of a bolster, a bearing member revolvably supported thereon, a steering post in said bearing member, wheels on which said bolster is supported, means operatively connecting said steering post with the wheels, a draft member mounted on said bearing member, and locking means for connecting said bearing member and said post. 100

6. In a wagon, the combination of a bolster, a bearing member revolvably supported thereon, a steering post in said bearing member, wheels on which said bolster is supported, means operatively connecting said 110 steering post with the wheels, a draft member mounted on said bearing member, and a spring pressed locking pin adapted to lock the bearing member to the post. 105

7. In a wagon, the combination of a bolster, an axle pivotally mounted at each end thereof, a rod connecting said axles to move them in unison, a steering rod operatively connected to said connecting rod, a bearing member rotatably supported on the bolster 115 and in which the steering rod has a bearing, a draft member mounted on the bearing member and means for locking the steering rod to the bearing member. 120

8. A wagon provided with pivotally 125 mounted wheels at the front thereof, a connection between said wheels, an arm pivotally mounted upon the center of said connection, a steering post rigidly connected with the arm, a tongue rotatably mounted 130

upon the steering post, and means adapted to be moved into locking engagement with the tongue for preventing movement of the same upon the steering post whereby to effect movement of said steering post upon movement of the tongue.

9. A wagon provided with pivotally mounted wheels at the front thereof, a manually controlled steering member operatively connected with the wheels for moving

the same upon their pivots, a rotatably mounted tongue support, means for connecting said support with said steering member for effecting movement of the same, and a tongue mounted on the support and movable to a position beneath the wagon.

HARRISON BUCKLIN.
